United States Patent Office

Des. 212,062
Patented Aug. 20, 1968

212,062

LETTER OPENER

Thomas H. Davis, Rocky River, Ohio, assignor to The General Industries, Elyria, Ohio, a corporation of Ohio

Filed May 15, 1967, Ser. No. 7,131

Term of patent 14 years

(Cl. D74—10)

Fig. 1

Fig. 2

Fig. 3

Fig. 4

Fig. 5

Fig. 6

FIG. 1 is a perspective view of the letter opener showing my new design as seen generally from the front and one end thereof;

FIG. 2 is a front elevational view thereof;

FIG. 3 is a rear elevational view thereof;

FIG. 4 is a top plan view thereof;

FIG. 5 is an end view thereof as seen from the right-hand end of FIGS. 1, 2 and 4 and the left-hand end of FIG. 3;

FIG. 6 is an end view thereof as seen from the left-hand end of FIGS. 1, 2 and 4 and the right-hand end of FIG. 3.

I claim:

The ornamental design for a letter opener, as shown.
